Application December 7, 1948, Serial No. 63,998

25 Claims. (Cl. 12—10.2)

1

This invention relates to machines for use in the manufacture of shoes and is herein illustrated in its application to a machine for pulling uppers over lasts. An immediate object in view is to provide certain improvements in pulling-over machines of a well-known type the main characteristic features of which are disclosed in United States Letters Patent No. 1,029,387, granted on June 11, 1912, on an application of R. F. McFeely. The invention is accordingly herein shown as applied to such a machine, but it is to be understood that in some of its novel and useful aspects it is not limited to machines of that type or to pulling-over machines.

A pulling-over machine of the above-mentioned type is provided with a toe gripper for pulling the upper at the end of the toe and with side grippers for pulling it respectively at the opposite sides of the forepart. Associated with the several grippers are wipers which, after the pulling of the upper, wipe its margin inwardly over the insole and tackers which are thereafter operated to drive tacks for fastening the upper in pulled-over position. A single tack is thus driven at the end of the toe and usually two tacks are driven at each side of the forepart, one tack at each side being preferably located substantially at the tip seam if the upper, as usual, is provided with a toe tip. The operator presents the shoe to the machine as accurately as he can in such manner that the toe gripper and the toe tacker are substantially central widthwise of the toe, the forepart of the last being between the side grippers and close to the inner jaws of these grippers. Because of the so-called "swing" of right and left lasts the heel end of a right shoe thus properly positioned is somewhat offset laterally toward one side of the machine and the heel end of a left shoe is correspondingly offset toward the other side of the machine, the extent of such offset with respect to a shoe of a given size depending upon the style of the shoe. To assist in controlling the shoe in the pulling-over operation there is provided a V-shaped heel rest which is moved lengthwise of the shoe into engagement with its heel end shortly after the starting of the cycle of operations of the machine after the grippers have gripped the upper and have begun to pull it. The heel rest initially occupies a substantially central position widthwise of the machine, but is so supported as to permit it to move laterally toward one side of the machine or the other side upon engagement with each shoe and therefore to adjust itself in accordance with the laterally offset positions of the heel ends of right and left shoes.

2

The present invention provides novel means for controlling the heel rest in such manner that instead of adjusting itself to each shoe as above described, it serves to determine the proper position of the heel end of each shoe laterally, whether it is a right shoe or a left shoe, and therefore insures the proper positioning of the forepart of each shoe in the above described relation to the grippers and the tackers without attention on the part of the operator. The construction shown comprises novel mechanism whereby the heel rest is swung automatically in directions widthwise of the machine to different initial positions adjustably determined in accordance with the style of the shoes operated upon and is thus properly positioned for use on right and left shoes of that style alternately. To render the heel rest thus properly effective in positioning each shoe prior to the starting of the machine, the construction shown is further such that the heel rest is engaged by the shoe when the operator presents the latter to the machine and is moved yieldingly from its initial predetermined position in a direction lengthwise of the shoe by pressure of the heel end of the shoe against it until the toe end of the shoe is properly positioned lengthwise relatively to the toe gripper, the direction of this movement of the heel rest being substantially parallel to the longitudinal median line of the heel end of the shoe, whether the shoe is a right shoe or a left shoe. The heel rest therefore assumes, in accordance with the length of the shoe, a position which is that required for properly positioning laterally the heel end of a shoe of that style and size.

The novel features of the invention, including various novel details of construction and combinations of parts, will now be more particularly described with reference to the accompanying drawings and thereafter pointed out in the claims.

In the drawings,

Fig. 1 is a view mainly in left-hand side elevation of a portion of the machine to which the invention is shown as applied, the parts being positioned as they are after a shoe has been presented but prior to the starting of the machine;

Fig. 2 is a view also mainly in left-hand side elevation, on an enlarged scale, of a portion of the structure shown in Fig. 1, illustrating by broken lines the positions of certain parts at a particular time in the operation of the machine;

Fig. 3 is a view on an enlarged scale in the direction of the arrow III in Fig. 1, with some parts omitted, the position of a right shoe being

indicated diagrammatically by a broken line as in Fig. 1;

Fig. 4 is a view similar to Fig. 3 of a portion of the structure, with the parts in the same positions as in Fig. 3 and with parts broken away;

Fig. 5 is a section on the line V—V of Fig. 3;

Fig. 6 is a section on the line VI—VI of Fig. 3; and

Fig. 7 is a section on the line VII—VII of Fig. 3.

A machine of the type above referred to is provided with a toe gripper 2 for gripping the margin of the upper and pulling the upper at the extreme end of the toe and with side grippers 6 for similarly operating on the upper at the opposite sides of the forepart. The side grippers include pairs of jaws 8 which act on the upper in the vicinity of the tip seam, when the shoe is provided with a tip, and include also pairs of jaws 10 which, in the use of the machine on adults' shoes, act on the upper in locations farther from the end of the toe than the jaws 8. Associated respectively with the different grippers are mechanisms comprising wipers and tackers for wiping the margin of the upper inwardly over an insole on the last and for driving tacks to fasten the upper in pulled-over position, the mechanism at the end of the toe being shown at 12 in Fig. 1 and one of the two mechanisms at the opposite sides of the forepart being shown at 14. At the end of the toe a single tack is thus driven by a tack driver 16, and by other drivers (not shown) at each side of the forepart a tack is driven substantially in the location of the tip seam and one or more other tacks farther from the end of the toe than the tip seam. Prior to the operations of the wipers and tackers the shoe is clamped and held by opposite side-clamps one of which is shown at 17 in Fig. 1.

The shoe is presented to the machine by the operator with the bottom of its forepart in engagement with a sole rest 18 having a presser foot 20 which engages the insole centrally near the end of the toe and other presser feet 22 which engage it in locations spaced apart widthwise of the shoe and farther from the end of the toe than the presser foot 20. In thus presenting the shoe the operator engages the toe-end face of the last with one of the jaws 4, namely the inner jaw, of the toe gripper, which thus determines the position of the shoe lengthwise in the machine, and positions the forepart of the last between the opposite side grippers the inner jaws of which are close to the sides of the last. If the shoe is properly presented the toe gripper and toe tacker will be centrally disposed widthwise of the toe so that the upper will be properly tensioned lengthwise and the tack will be driven substantially on the longitudinal median line of the forepart of the shoe. This requires that the heel end of a right shoe be somewhat offset laterally toward one side of the machine and the heel end of a left shoe be correspondingly offset toward the other side of the machine. The present invention provides novel means whereby the position of the shoe in this respect, whether it is a right shoe or a left shoe, is automatically determined. For this purpose a V-shaped heel rest 24, which is itself substantially like the heel rests of prior machines of the above-mentioned type, is moved laterally to different predetermined positions for right and left shoes respectively. By means of pins 26 (Figs. 1 and 7) this heel rest is pivotally supported on two spaced arms 28 of a holder 30 for tipping movement about an axis extending widthwise of the shoe

to permit it to adjust itself in this respect to the shoe, such movement of the heel rest being limited by a screw 32 which is threaded therein and extends through a slot 34 formed in an extension 36 of one of the arms 28. The holder 30 is secured by two screws 38 (Fig. 6) to a slide 40 movable in directions lengthwise of the shoe, the holder having a tongue 42 (Fig. 7) which fits in a groove 44 in the slide. To permit the heel rest to be differently positioned relatively to the slide 40 for better accommodation to shoes of different lengths, the slide 40 is provided with a plurality of such grooves 44 with corresponding holes to receive the screws 38. The slide 40 is guided for movements in directions lengthwise of the shoe by a guideway in a carrier 46 supported as hereinafter described. Mounted in a bore in the slide is a tension spring 48 which is connected at one end to a pin 50 on the slide and at its other end to a pin 52 on the carrier 46, the spring being partly housed within a casting 53 on the carrier. The spring, therefore, tends to move the slide 40 and the heel rest 24 in the direction to hold the heel rest against the shoe and positions the heel rest initially nearer the grippers 2 and 6 than when there is a shoe in the machine. Accordingly, in presenting a shoe the operator places its heel end against the heel rest and by pressure of the shoe on the heel rest moves the latter against the resistance of the spring 48 until the toe end of the last is in proper position to engage the inner jaw of the toe gripper 2. When there is no shoe in the machine movement of the heel rest toward the grippers is limited by a pin 54 slidably mounted in the heel rest holder 30 and extending into one or the other of two slots 56 (Fig. 4) formed in the carrier 46. It will be understood that in thus limiting movement of the heel rest the pin engages the carrier at one end of either slot. The two slots are provided to permit a preliminary adjustment of the heel rest for comparatively large shoes or comparatively small shoes, so that in presenting a large shoe the operator will not have to move the heel rest so far against the resistance of the spring 48 as he would if there were no provision for such adjustment. In making the adjustment the operator withdraws the pin 54 from one of the slots 56 against the resistance of a leaf spring 58 which controls it, and after moving the heel rest to the proper position causes the pin to enter the other slot. It will be understood that the provision for securing the heel rest holder 30 in different positions along the slide 40 in the manner hereinbefore described permits a more precise initial adjustment of the heel rest for shoes of different sizes.

The carrier 46, which supports the heel rest as above described, is mounted for swinging movements in directions widthwise of the shoe to carry the heel rest laterally to different initial positions for right and left shoes respectively. For this purpose one end of the carrier is pivotally connected by studs 60 to arms 62 of two bell-crank levers 64 pivotally mounted on studs 66 which are supported in lugs 68 on a bracket 70. This bracket has formed thereon two ribs 71 which are secured to bars 72, these bars being held by binding screws 74 in fixed positions in grooves 76 formed in the head casting 78 of the pulling-over machine. The arrangement of the bell-crank levers 64 is such that as they are both swung, by means hereinafter described, in clockwise directions or in counterclockwise directions 75 with reference to Fig. 3, they guide the heel rest

carrier 46 for swinging movements substantially about an axis located at x (Fig. 3), the location of this axis being approximately at the junction of the longitudinal median lines of the forepart and heel part of a shoe in the machine. The heel rest 24 is thus carried to the different positions required for right and left shoes. To assist further in guiding and controlling the carrier 46 in its swinging movements, two members 80 and 82 are secured respectively to the opposite ends of the carrier, the member 80 overlapping and cooperating with an arcuate guide 84 fast on the bracket 70 and the member 82 being similarly arranged in relation to an arcuate tongue 86 formed on the bracket. To limit the swinging movements of the carrier 46 and thus to determine the proper initial positions of the heel rest for right and left shoes, there are provided stops 88 arranged to be engaged respectively by the opposite sides of the carrier, these stops being mounted for movements toward and from each other along guideways on the bracket 70. A shaft 90 rotatable in the bracket by means of knobs 92 on its ends is provided with right and left screw threads in engagement with the stops for adjusting them equal distances toward or from each other as required for shoes of different styles.

For operating the bell-crank levers 64 to swing the carrier 46 there is provided a bar 94, shown best in Fig. 7, which is guided for lengthwise movements by the bracket 70 and by a member 95 on the bracket and an end portion of which is arranged to slide on the carrier. This end portion of the bar has thereon a flanged head 96 arranged to engage inwardly extending arms 98 of the bell-crank levers 64. By reference to Figs. 3 and 4 it will be seen that when the heel rest carrier 46 is in the position there shown the arm 98 of one of the bell-crank levers is close to the head 96 of the bar 94 while the corresponding arm of the other bell-crank lever is at a considerable distance from the head 96. Upon rearward movement of the bar, therefore, it serves to swing the first-mentioned bell-crank lever in the direction to reverse the position of the heel rest carrier 46. Since the other bell-crank lever swings simultaneously in the same direction, its arm 98 in this operation approaches the head 96. Accordingly the movement of the bar 94, effected as hereinbefore described, is a short movement and serves only to initiate the swinging of the carrier 46. To complete the movement of the carrier there is provided what may be termed a reversing device 100. This device comprises two telescopic tubular members 102 and 104 pivotally connected respectively to the bracket 70 and the carrier 46 and having therein an expansion spring 106 (Fig. 4). The device is so arranged relatively to the carrier 46 that it is swung past a dead-center position by the swinging movement of the carrier. This movement, as above stated, is initiated by the bar 94, the momentum of the carrier and of the parts thereon assisting in the swinging of the device 100 past dead center. After the device passes dead center the spring 106 by its expansion completes independently the swinging movement of the carrier, the spring thereafter holding the carrier in the position determined by the appropriate stop 88. It will be understood that as the carrier is thus swung the positions of the bell-crank levers 64 are reversed, so that in response to the next rearward movement of the bar 94 the carrier is returned to

its first position, the bar acting on the arm 98 of the other bell-crank lever.

The bar 94 is connected at its rear end by a link 103 to an arm 105 which is fast on a shaft 107 mounted to turn in the bracket 70 and in one of the bars 72. Also fast on this shaft is an arm 108 connected by a link 110 to an arm 112 mounted to swing about a pin 114 on the head casting 78, the arm 112 having integral therewith an upwardly extending arm 116. The upper end of this arm is in the path of a dog 118 pivotally mounted in the forked lower end of a member 120 which is carried by a slide 122 movable horizontally in rearward and forward directions in the head casting 78, the slide being operated by a rotatable path cam 124 engaging a roll 126 thereon. The slide 122 corresponds to the slide 10 shown in Letters Patent No. 1,029,387 for moving the heel rest of the machine therein shown forwardly into engagement with the heel end of the shoe in the first stage of the cycle of operations of the machine. The slide 22, therefore, is moved in a rearward direction in the first stage of the cycle, and as it moves in that direction the dog 118 is carried idly past the arm 116 since it turns relatively to the member 120 upon contact with the arm, as illustrated by broken lines in Fig. 2. Near the end of the cycle, after the operations on the shoe have been completed, the slide is moved reversely in a forward direction, and at that time the dog 118 is prevented from turning relatively to the member 120 by its engagement with a shoulder 128 on this member. Accordingly the arm 116 is swung forwardly by the dog until the latter passes beyond it, thus imparting to the bar 94 the amount of movement required to operate one or the other of the bell-crank levers 64 in the manner hereinbefore described. The position of the heel rest 24 is therefore reversed near the end of each cycle, after the shoe has been released, so that it will be in positions for use on right and left shoes alternately. The dog 118 passes beyond the arm 116 by the time the head 96 of the bar 94 is engaged by that arm 98 which is approaching it as hereinbefore described, after which continued movement of that arm 98, as the reversal of the heel rest carrier 46 is completed by the device 100, serves to return the bar 94 to its initial position. Such return movement of the bar may be limited by its engagement with that portion of the bracket 70 which is adjacent to the tongue 86.

The manner of operation of the machine, in so far as it is of interest with reference to the present invention, will now be briefly summarized. The heel rest 24 is initially in a position widthwise of the machine appropriate for either a right shoe or a left shoe, and if it is not in position for the shoe which the operator first takes up he may swing it to that position by hand, the spring 106 being sufficiently yieldable to permit this readily to be done. The stops 88 will be preliminarily adjusted as required by shoes of the style to be operated upon and the slide 40 will be properly positioned initially for a range of sizes as determined by the pin 54 and one or the other of the slots 56. In presenting the shoe to the machine the operator places its heel end against the heel rest and by the pressure of the shoe on the heel rest moves the latter against the resistance of the spring 48 until the toe-end face of the last is in position to engage the inner jaw 4 of the toe gripper 2, the bottom of the forepart 70 of the shoe then engaging the sole rest 18. At

the same time the operator positions the marginal portion of the upper materials properly between the jaws of the toe and side grippers. In thus presenting the shoe the operator has no concern as to its position angularly, i. e., with respect to lateral swinging movement of its heel end, since this is determined by the heel rest. Accordingly insurance is afforded that the toe gripper and toe tacker are centrally disposed widthwise of the toe and also that the foremost side tacks will be located in proper relation to the tip seam. The heel rest properly functions in this respect in positioning shoes of different sizes, since the direction of its movement along its carrier 46 is substantially parallel to the longitudinal median line of the heel end of the shoe. That is, the heel rest assumes, in accordance with the length of the shoe, the position required for properly positioning laterally the heel end of a shoe of that style and size, as predetermined by the position of the heel rest carrier 46 in engagement with one or the other of the adjustable stops 88. It will be understood that in pulling-over machines of the type shown the toe gripper 2 and the presser foot 20 of the sole rest 18 are customarily adjusted in directions lengthwise of the shoe for shoes of different sizes so that the junction of the longitudinal median line of the forepart and that of the heel part of each shoe will be located approximately as indicated at x (Fig. 3) irrespective of size variations.

Having presented the shoe as above described, the operator starts the power operation of the machine, whereupon the grippers grip and pull the upper, the machine then coming to a stop to permit inspection of the upper and any necessary adjustment. In this first stage of the cycle the slide 122 is moved in a rearward direction, the dog 118 passing idly over the arm 116. After the machine has been started a second time, the side clamps 17 are moved inwardly to clamp and hold the shoe at the sides of the forepart and the wiping and tacking mechanisms 12 and 14 are then operated to wipe the margin of the upper inwardly over the insole and to drive the upper-fastening tacks, the grippers releasing the upper. Thereafter the parts which operate on the shoe are returned to starting positions and the shoe is released by the side clamps, the operator holding it in his hand to prevent it from falling. Near the end of the cycle the slide 122 is moved forwardly and causes the dog 118 to swing the arm 116 in that direction. This serves to move the bar 94 in a rearward direction, causing the head 96 on the bar to engage that arm 98 which is adjacent thereto and to start the swinging movement of the bell-crank lever 64 of which that arm is a part, thus initiating the reversal of the heel rest. The impulse thus imparted to the heel rest carrier 46 is sufficient to swing the reversing device 100 past dead center, whereupon the spring 106 of this device expands to complete the movement of the carrier into engagement with one of the stops 88. In this manner the position of the heel rest is reversed after the operation of the machine on one shoe of a pair preparatory to its operation on the other shoe of the pair in the next cycle. As the spring 106 thus completes the movement of the heel rest carrier the bar 94 is returned by the action of the arm 98 of one of the bell-crank levers 64 thereon in the manner hereinbefore explained.

Having described the invention, what I claim as new and desire to secure by Letters Patent of the United States is:

1. In a shoe machine, the combination with means for operating on the foreparts of right and left shoes, of a heel rest for determining the position of the heel end of each shoe laterally by engagement with that end of the shoe, and means supporting said heel rest for lateral movements in opposite directions to different predetermined positions for right and left shoes respectively and also for movement in a direction lengthwise of each shoe in response to pressure of the heel end of the shoe thereon when the operator presents the shoe to the machine.

2. In a shoe machine, the combination with means for operating on the foreparts of right and left shoes, of a heel rest for determining the position of the heel end of each shoe laterally by engagement with that end of the shoe, and means supporting said heel rest for lateral movements in opposite directions to different predetermined initial positions for right and left shoes respectively and also for movement from each of said positions in a direction substantially parallel to the longitudinal median line of the heel end of the shoe in response to pressure of the shoe thereon when the operator presents the shoe to the machine.

3. In a shoe machine, the combination with means for operating on the foreparts of right and left shoes, of a heel rest for determining the position of the heel end of each shoe laterally by engagement with that end of the shoe, and means supporting said heel rest for swinging movements laterally in opposite directions about an axis located approximately at the junction of the longitudinal median lines of the forepart and heel part of the shoe to different predetermined positions for right and left shoes respectively, the heel rest being further mounted for movement in a direction substantially parallel to the longitudinal median line of the heel end of each shoe in response to pressure of the shoe thereon when the operator presents the shoe to the machine.

4. In a shoe machine, the combination with means for operating on the foreparts of right and left shoes, of a heel rest for determining the position of the heel end of each shoe laterally by engagement with that end of the shoe, means supporting said heel rest for lateral movements in opposite directions to different predetermined positions for right and left shoes respectively and also for movement in a direction lengthwise of each shoe in response to pressure of the heel end of the shoe thereon when the operator presents the shoe to the machine, and stops for adjustably limiting said lateral movements of the heel rest.

5. In a shoe machine, the combination with means for operating on the foreparts of right and left shoes respectively in successive cycles of operations of the machine, of a heel rest for determining the position of the heel end of each shoe laterally by engagement with that end of the shoe, and means for moving said heel rest laterally to one position for a right shoe in one cycle of operations and to another position for a left shoe in the next cycle of operations, said heel rest being mounted for movement from each of said positions in a direction lengthwise of the shoe in response to pressure of the heel end of the shoe thereon when the operator presents the shoe to the machine.

6. In a shoe machine, the combination with means for operating on the foreparts of right and left shoes, of a V-shaped heel rest for determining the position of the heel end of each shoe lat-

erally by engagement with the upper at that end of the shoe, means supporting said heel rest for lateral movements in opposite directions to different predetermined positions for right and left shoes respectively and also for movement from each of said positions in a direction substantially parallel to the longitudinal median line of the heel end of the shoe in response to pressure of the shoe thereon when the operator presents the shoe to the machine, and means for yieldingly opposing said last-named movement of the heel rest.

7. In a shoe machine, the combination with means for operating on the foreparts of right and left shoes successively, of a heel rest for determining the position of the heel end of each shoe laterally by engagement with that end of the shoe, means supporting said heel rest for lateral movements in opposite directions to different predetermined initial positions for right and left shoes respectively, and automatic means for moving the heel rest from one of said positions to the other position after the operation of the machine on each shoe, the heel rest being further mounted for movement from each of said positions in a direction lengthwise of the shoe in response to pressure of the heel end of the shoe thereon when the operator presents the shoe to the machine.

8. In a shoe machine, the combination with a toe gripper and side grippers for pulling an upper over a last respectively at the end of the toe and the sides of the forepart, of a heel rest for determining the position of the heel end of each shoe laterally by engagement with the upper at that end of the shoe and for thereby determining the position of the toe end of the shoe widthwise relatively to the toe gripper, and means supporting said heel rest for lateral movements in opposite directions to different positions for right and left shoes respectively and also for movement from each of said positions in a direction substantially parallel to the longitudinal median line of the heel end of the shoe in response to pressure of the shoe thereon when the operator presents the shoe to the machine.

9. In a shoe machine, the combination with a toe gripper and side grippers for pulling an upper over a last respectively at the end of the toe and the sides of the forepart, of a heel rest for determining the position of the heel end of each shoe laterally by engagement with the upper at that end of the shoe and for thereby determining the position of the toe end of the shoe widthwise relatively to the toe gripper, means supporting said heel rest for lateral movements in opposite directions to different positions for right and left shoes respectively, and automatic means for thus moving the heel rest to said different positions successively, the heel rest being further mounted for movement from each of said positions in a direction substantially parallel to the longitudinal median line of the heel end of the shoe in response to pressure of the shoe thereon when the operator presents the shoe to the machine.

10. In a shoe machine, the combination with a toe gripper and side grippers for pulling an upper over a last respectively at the end of the toe and the sides of the forepart, said toe gripper being arranged to determine the position of the shoe lengthwise by engagement with the toe-end face of the last, of a heel rest for determining the position of the heel end of each shoe laterally by engagement with the upper at that end of the

shoe and for thereby determining the position of the toe end of the shoe widthwise relatively to the toe gripper, and means supporting said heel rest for lateral movements in opposite directions to different positions for right and left shoes respectively, the heel rest being further mounted for movement in a direction lengthwise of each shoe in response to pressure of the heel end of the shoe thereon until the toe-end face of the last is in position to engage the toe gripper when the operator presents the shoe to the machine.

11. In a shoe machine, the combination with means for operating on the foreparts of right and left shoes, of a heel rest for determining the position of the heel end of each shoe laterally by engagement with that end of the shoe, and a heel rest carrier supporting said heel rest and mounted for swinging movements to carry the heel rest laterally in opposite directions to different predetermined positions for right and left shoes respectively, the heel rest being mounted to move relatively to said carrier in a direction substantially parallel to the longitudinal median line of the heel end of the shoe in response to pressure of the shoe thereon when the operator presents the shoe to the machine.

12. In a shoe machine, the combination with means for operating on the foreparts of right and left shoes, of a heel rest for determining the position of the heel end of each shoe laterally by engagement with that end of the shoe, a heel rest carrier supporting said heel rest and mounted for swinging movements to carry the heel rest laterally in opposite directions to different predetermined positions for right and left shoes respectively, the heel rest being mounted to move relatively to said carrier in a direction lengthwise of each shoe in response to pressure of the heel end of the shoe thereon when the operator presents the shoe to the machine, and a spring for yieldingly opposing such movement of the heel rest by the shoe.

13. In a shoe machine, the combination with means for operating on the foreparts of right and left shoes respectively in successive cycles of operations of the machine, of a heel rest for determining the position of the heel end of each shoe laterally by engagement with that end of the shoe, a heel rest carrier mounted for swinging movements in opposite directions to carry the heel rest laterally to different positions for right and left shoes respectively, and automatic means for thus swinging said carrier to carry the heel rest into position for a right shoe in one cycle of operations and into position for a left shoe in the next cycle of operations, the heel rest being mounted to move relatively to said carrier in a direction lengthwise of each shoe in response to pressure of the heel end of the shoe thereon when the operator presents the shoe to the machine.

14. In a shoe machine, the combination with means for operating on the foreparts of right and left shoes, of a heel rest for determining the position of the heel end of each shoe laterally by engagement with that end of the shoe, a heel rest carrier mounted for swinging movements in opposite directions to carry the heel rest laterally to different predetermined positions for right and left shoes respectively, and stops for engaging said carrier to limit adjustably its swinging movements, the heel rest being mounted to move relatively to the carrier in a direction lengthwise of each shoe in response to pressure of the heel end of the shoe thereon when the operator presents the shoe to the machine.

11

15. In a shoe machine, the combination with means for operating on the foreparts of right and left shoes, of a heel rest for determining the position of the heel end of each shoe laterally by engagement with that end of the shoe, a heel rest carrier supporting said heel rest, and members mounted for movements about different axes extending heightwise of the shoe and pivotally connected to said heel rest carrier respectively in different locations to guide the carrier for swinging movements in opposite directions to carry the heel rest laterally to different positions for right and left shoes respectively.

16. In a shoe machine, the combination with means for operating on the foreparts of right and left shoes, of a heel rest for determining the position of the heel end of each shoe laterally by engagement with that end of the shoe, a heel rest carrier supporting said heel rest, and members mounted for movements about different axes extending heightwise of the shoe and pivotally connected to said heel rest carrier respectively in different locations to guide the carrier for swinging movements in opposite directions about an axis located approximately at the junction of the longitudinal median lines of the forepart and heel part of the shoe to carry the heel rest laterally to different positions for right and left shoes respectively.

17. In a shoe machine, the combination with means for operating on the foreparts of right and left shoes respectively in successive cycles of operations of the machine, of a heel rest for determining the position of the heel end of each shoe laterally by engagement with that end of the shoe, a heel rest carrier supporting said heel rest, members mounted for movements about different axes extending heightwise of the shoe and pivotally connected to said heel rest carrier respectively in different locations to guide the carrier for swinging movements to carry the heel rest laterally to different positions for right and left shoes respectively, and automatic means for thus swinging said carrier to carry the heel rest into position for a right shoe in one cycle of operations of the machine and into position for a left shoe in the next cycle of operations.

18. In a shoe machine, the combination with means for operating on the foreparts of right and left shoes, of a heel rest for determining the position of the heel end of each shoe laterally by engagement with that end of the shoe, a heel rest carrier supporting said heel rest, bell-crank levers mounted for swinging movements about different axes extending heightwise of the shoe and pivotally connected to said heel rest carrier respectively in different locations to guide the carrier for swinging movements in opposite directions to carry the heel rest laterally to different positions for right and left shoes respectively, and means for thus swinging said carrier in one direction by force applied to one of said bell-crank levers and in the opposite direction by force applied to the other bell-crank lever.

19. In a shoe machine, the combination with means for operating on the foreparts of right and left shoes, of a heel rest for determining the position of the heel end of each shoe laterally by engagement with that end of the shoe, a heel rest carrier supporting said heel rest, bell-crank levers mounted for swinging movements about different axes extending heightwise of the shoe and pivotally connected to said heel rest carrier respectively in different locations to guide the carrier for swinging movements in opposite di-

12

rections to carry the heel rest laterally to different positions for right and left shoes respectively, and an operating member mounted for reciprocating movements and arranged to act on one of said bell-crank levers to swing said carrier in one direction and on the other bell-crank lever to swing the carrier in the other direction.

20. In a shoe machine, the combination with means for operating on the foreparts of shoes, of a heel rest for engaging the heel end of each shoe to control the shoe, a member movable to carry the heel rest along a path extending lengthwise of each shoe in response to pressure of the heel end of the shoe on the heel rest when the operator presents the shoe to the machine, a spring for yieldingly opposing the movement of the heel rest along said path, another member relatively to which said first-named member and the heel rest are thus movable, one of said members having slots therein in different locations lengthwise of the path of movement of the heel rest, and a pin on the other member arranged to be inserted in said different slots selectively to position the heel rest initially in different locations along its path of movement for shoes of different lengths while permitting it to be moved from each of said locations against the resistance of the spring by the pressure of the shoe thereon.

21. In a shoe machine, the combination with means for operating on the foreparts of shoes, of a heel rest for engaging the heel end of each shoe to control the shoe, a slide to which the heel rest is secured, a support having a guideway for said slide to permit the heel rest to be moved along a path extending lengthwise of each shoe in response to pressure of the heel end of the shoe thereon when the operator presents the shoe to the machine, a spring for yieldingly opposing such movement of the heel rest, said support having slots therein in different locations along the path of movement of the heel rest, and a pin movable with the heel rest and arranged to be inserted in said different slots selectively to position the heel rest initially in different locations along its path of movement for shoes of different lengths while permitting it to be moved from each of said locations against the resistance of the spring by the pressure of the shoe thereon.

22. In a shoe machine, the combination with means for operating on the foreparts of right and left shoes, of a heel rest for engaging the heel end of each shoe to control the shoe, said heel rest being mounted for lateral movements to different positions for right and left shoes respectively, means for initiating movement of the heel rest from either of said positions toward the other position, and additional means for completing independently the movement of the heel rest thus initiated.

23. In a shoe machine, the combination with means for operating on the foreparts of right and left shoes, of a heel rest for engaging the heel end of each shoe to control the shoe, said heel rest being mounted for lateral movements to different positions for right and left shoes respectively, means for initiating movement of the heel rest from either of said positions toward the other position, and spring means mounted for movement past a dead center position for thereafter completing independently the movement of the heel rest thus initiated.

24. In a shoe machine, the combination with means for operating on the foreparts of right and left shoes, of a heel rest for engaging the

13

heel end of each shoe to control the shoe, a heel rest carrier mounted for movements in opposite directions to carry the heel rest laterally to different positions for right and left shoes respectively, means for initiating movement of said carrier to carry the heel rest from either of said positions toward the other position, and a device mounted for swinging movement past a dead center position by the movement of the carrier thus initiated, said device comprising two telescopic members and a compression spring therein for completing the movement of the carrier after the device has passed its dead center position.

25. In a shoe machine, the combination with means for operating on the foreparts of right and left shoes, of a heel rest for engaging the heel end of each shoe to control the shoe, a heel rest carrier supporting said heel rest, bell-crank levers mounted for swinging movements about different axes extending heightwise of the shoe and pivotally connected to said heel rest carrier

14

respectively in different locations to guide the carrier for swinging movements in opposite directions to carry the heel rest laterally to different positions for right and left shoes respectively, 5 means for initiating movement of said carrier in one direction by force applied to one of said bell-crank levers and in the opposite direction by force applied to the other bell-crank lever, and spring means mounted for movement past a dead center position by each movement of the carrier thus initiated for thereafter completing that movement of the carrier.
